UNITED STATES PATENT OFFICE.

JOSEPH V. ROBINSON, OF BRANFORD, CONNECTICUT.

TRAIN-PIPE CONNECTOR.

1,245,773.

Specification of Letters Patent.

Patented Nov. 6, 1917.

Application filed March 25, 1911, Serial No. 616,906. Renewed September 13, 1917. Serial No. 191,303.

To all whom it may concern:

Be it known that I, JOSEPH V. ROBINSON, a citizen of the United States, residing at Branford, in the county of New Haven, State of Connecticut, have invented certain new and useful Improvements in Train-Pipe Connectors, of which the following is a specification.

My invention relates to improvements in trainpipe connectors or couplers, and it consists in the constructions, combinations, and arrangements hereinafter described and claimed.

An object of my invention is to provide an improved trainpipe connector constructed to connect with certainty, and to maintain an efficient connection, under all service conditions.

A further object of my invention is to provide a compact and simple trainpipe connector which will operate with freedom from excessive battering blows and deteriorating binding, or "jamming".

A further object of my invention is to provide a compact and simple trainpipe connector adapted to be applied for efficient operation to all existing rolling stock.

In the accompanying drawings, forming a part of this application and in which similar reference symbols indicate corresponding parts in the several views:

Figure 1 is a side elevation, with parts broken away, illustrating one embodiment of my invention attached to standard draft 35 coupler; Fig. 2 is a front elevation of the connector shown in Fig. 1; Fig. 3 is a sectional elevation on the line 3—3 of Fig. 1; Fig. 4 is an enlarged perspective view of one of the spring-securing plates shown in Fig. 40 3; Fig. 5 is a side elevation of the support with a fragment of the spring secured thereto, and Fig. 6 is a front elevation of the same.

Referring to the drawings, 1 indicates an 45 attaching lug, which may be formed integral with or suitably secured to a standard draft coupler 2, said lug being provided with slots 3 and a head 4 formed with inclined or tapered shoulders 5.

50 A connector bracket or support 6 is provided with jaws 7 which are adjustably se-

cured to the lug 1 by bolts 8 extending through the slots 3 of the latter, said jaws being preferably rendered resilient by a medial slit 9 and provided with inclined faces 55 10 for clamping the lug shoulders 5 with a strong wedging action when secured in position. The bracket 6 is provided with a flaring socket 11 and a co-axial annular seat 12' on which the base coil of a conical spiral 60 spring 12 is rigidly secured by a series of dogs 13; the end of said base coil 12 being offset to engage a notch 12' in said bracket for positively anchoring said spring against rotation. I have shown an exceedingly 65 strong and rigid construction in which the dogs 13 are secured to the bracket by bolts 14 and extend over the base spring coil into recesses or radial sockets 15 in a hub or projection 15' which extends forwardly from 70 the bracket through the base coil of the spring 12 and within the adjacent free coil thereof, to constitute a rest or limiting stop for the latter, thereby efficiently preventing 75 injurious localization of stresses in the 75 spring.

A connector head 16 is shown provided with a tubular connection 17 extending freely through the flaring socket 11 for connection with the air-brake pipe, and with 80 integral pipe nipples 18 and 19 for connection with the signal pipe and steam-heat pipe, respectively. The socket 11, however, constitutes a means for limiting the extent 85 of oscillation of the head and its connection 17. The nipples 18 and 19 diverge in a common plane from the rear face of the head 16 to provide a seat 20 for the apex coil of the spring 12, said spring being formed of gradually tapered stock and terminating in 90 an offset portion 21 for entering an anchoring recess 22 in the seat 20. Securing plates 23 are bolted at 24 to the head 16 and extend over the apex coil and into a recess 25 in the tubular connection 17 for rigidly securing 95 the spring on the head seat 20.

This novel construction and combination permits the employment of an efficiently small connector head and provides means for resisting all rotation of said head about 100 its axis and shifting of such axis from the normal connecting position by a varying re-

silient force increasing in greater progression than the extent of such rotation and shifting. This action is due to the general tapering form of the spring 12 and the fact 5 that the coils gradually decrease in cross section from the base to the smaller end of the spring, thus supporting the coupler head with very slight resistance to initial rotation and backward movement, which resist- 10 ances increase in ratio greater than the extent of such movements.

The front face of the head 16 is provided with any usual gaskets 26 for sealing the orifices of the air-brake and usual connec- 15 tions, and with a preferably metallic member 27 surrounding the orifice of the steam-heat connection, said member 27 being pro- 20 vided with a zone-shaped face for rockingly supporting a seat member or annulus 28, which latter is maintained in position by a spring clip 29. The seat or contact member 28 can advantageously be formed of brass and is provided with an annular groove for 25 receiving a sealing member, or filler, 30 of zinc or other suitable material having a greater coefficient of expansion and preferably of a different degree of hardness, said sealing member being thus confined against all lateral expansion. The sealing member 30 ex- 30 tends flush with the plane face of the contact member 28 to constitute therewith a compound packing face for insuring an efficient seal with the similar packing face of a co- 35 operating head when connected therewith.

35 The front face of the head is provided with two contact members 31 which project in a common plane with said compound packing face, thereby giving a three-point contact between pairs of connected heads 40 and insuring the maintenance of an efficient seal between the coöperating packing faces.

The connector head 16 is shown provided with the guides or collectors 32 and associated sockets 33 of an approved design 45 which need not be further described here.

I have illustrated preferred and satisfactory constructions, but changes could be made within the spirit and scope of my invention.

50 Having thus described my invention, what I claim as new and desire to secure by Letters Patent is:

1. In an automatic train pipe coupler, the combination of a coupler head, resilient means for resisting all rotation of the latter about its axis and shifting of such axis from the normal coupling position by a varying force increasing in greater progression than the extent of such rotation and shifting, and 55 means for positively limiting the swing of such axis.

2. In an automatic train pipe coupler, the combination of a coupler head, a spring supporting said head, a bracket provided

with an extension having a recess, and means 65 projecting into said recess for securing said spring to said bracket.

3. In a device of the character set forth, the combination with a support and a coiled spring, of means for securing the spring to 70 the support comprising a plurality of dogs spaced approximately an equal distance apart and embracing the base coil of said spring and clamping the same rigidly to the support, each dog having positive connection 75 with the support on opposite sides of the portion of the coil embraced thereby.

4. In a device of the character set forth, the combination of a support having an opening and a hub projecting therefrom, a 80 head having a member extending through said hub, a coiled spring between the head and the support and surrounding said hub, and a plurality of dogs interlocked with the support and the hub and embracing the 85 base coil of the spring.

5. In a device of the character set forth, the combination of a support having a hub 90 provided with a plurality of radially disposed sockets, a head having a member extending into said hub, a coiled spring between the head and the support and whose base coil surrounds said hub, and a plurality of devices rigidly securing the spring in place, each device projecting at one end into 95 one of the hub sockets and embracing the base coil of the spring.

6. In a device of the character set forth, the combination of a support having an opening, an annular seat surrounding the 100 same, and a hub projecting therefrom between the seat and the opening, a head having a member extending into said support opening, a coiled spring between the head and said seat, and devices secured to both the 105 support and its hub and embracing the base coil of the spring.

7. In a device of the character set forth, the combination of a support having an opening surrounded by a projection having 110 radial sockets, a head having a member extending into said opening, a coiled spring between the head and the support, the base coil of the spring surrounding said projection, and a set of dogs clamping said base 115 coil to the support, each dog being secured at one end to the support and at its other end in one of said sockets.

8. The hereindescribed coupler head having a plane face adapted to make butt connection with a similar head, said face being provided with a plurality of spaced contact points, one of which comprises an annulus of hard material having a groove and a 120 filler in said groove normally flush with said 125 annulus.

9. The hereindescribed coupler head having a plane face adapted to make butt con-

nection with a similar head, said face being provided with a plurality of spaced contact points, one of which comprises an annulus of hard material having a groove and a filler in said groove normally flush with said annulus, said filler having a higher coefficient of expansion than that of the annulus.

In testimony whereof I affix my signature in presence of two witnesses.

JOSEPH V. ROBINSON.
